Attorney

Patented Mar. 22, 1927.

UNITED STATES PATENT OFFICE.

EDWARD O. YOUNG, OF CLEVELAND HEIGHTS, OHIO.

INDIVIDUAL TOE EXPANDER FOR SHOE UPPERS.

Application filed February 18, 1926. Serial No. 89,093.

The invention relates to improvements in shoe stretching devices and has for its particular object means for stretching the upper of the shoe at definite points to relieve the pressure upon corns or bunions upon the toes, without distorting the entire fore part of the shoe. The invention includes individual toe members, connected with a common support and separate means in each toe member for expanding the same, so that the only portion of the upper affected thereby will be that portion closely adjacent to the toe upon which the corn or bunion is to be found.

15 Also the several toe members are specially shaped to correspond with their position in the shoe and are detachable and interchangeable and may be specially constructed to effect expansion of the upper at the desired 20 points in the shoe only. The side members such as the big and little toe members may be revolvable on their longitudinal axes, to enable them to expand either in a vertical or lateral direction or at angle therebetween to 25 accommodate themselves to the position of the corn or bunion on the foot, and the intermediate toe members may only be expansible in a vertical direction at the will of the operator.

30 The invention comprises longitudinally divided toe members, means for laterally and selectively expanding said toe members, and a common support therefor in which all the toe members are revolvable.

35 The invention is hereinafter more fully described, illustrated in the accompanying drawings and specifically pointed out in the claims.

In the accompanying drawings, Fig. 1 is 40 a plan of the device showing in dotted lines its position in the shoe.

Fig. 2 is an end elevation thereof, Fig. 3 is a transverse section of the toe members, Fig. 4 is a longitudinal section of the big 45 toe member, and Fig. 5 is a transverse section thereof.

In these views A represents the big toe member; B, B, B, represent the intermediate toe members and C the little toe member. All these members are longitudinally divided for vertical or lateral expansion.

D is a metal band encircling the toe members at their larger ends and embedded in grooves E, E, therein, thus retaining the toe 50 members in closely assembled relation therein, and also permitting them to revolve upon

their longitudinal axes to accommodate the direction of expansion to the position of the corns or bunions upon the toes. The sides of the enclosing band may be held together 60 with adjustable tension by means of bolts or screws F, F, if desired. To expand the toe members each pair of longitudinally directed sections thereof is provided with the tapered internal screw thread G, G, adjacent to the outer ends thereof, and a screw H is engaged with the threads of the tapered portions and by turning the screw the sections will be separated as far as may be desired, the amount of expansion being only limited 70 by the diameter of the screw.

When the corn or bunion is on the side of one of the outer toes, the toe member may be revolved on its axis to permit lateral expansion as shown in Fig. 3, or the toe members may be vertically expanded as shown in the Figure 3. An additional amount of expansion can be produced to accommodate local swelling, by enlarging the toe member at that point as at I, Fig. 5, or specially a 80 shaped toe member may be substituted in place of the one originally furnished.

In this manner all toe members can be detachably secured together and others substituted therefor if desired.

85 The device may be constructed of wood or metal or other suitable material, and is efficient and practical in use, and economical in its initial cost.

The screws may be provided with square 90 heads or other adjusting means and several may be turned so as to expand the entire upper if desired, or one toe member can be expanded to make the desired impression 95 upon the upper to protect a corn or bunion at any one location on the foot.

Having described the invention what I desire to secure by Letters Patent is:

1. In a device of the character described, a multiple number of longitudinally divided 100 toe members closely assembled for insertion between the upper and sole of a shoe in parallel relation to each other, a common transverse support for the rear extremities of said toe members in which said toe members are revolvable upon their longitudinal axes and in which the divisions of each toe member are pivotally secured in such a manner as to permit the separation of their outer ends and a separate internal expanding means for each toe member.

110 2. In a device of the character described,

a multiple number of longitudinally divided toe members, and individual means for expanding the same, and a common support for said toe members in which said toe members are separately revolvable.

3. In a device of the character described, a multiple number of longitudinally divided toe members, and individual means for expanding the same, and a common support 10 for said toe members, the sections of said toe members being pivotally secured adjacent in their larger ends to said common support and individually revolvable therein.

4. In a device of the character described, 15 a multiple number of longitudinally divided toe members, and individual means for expanding the same, and a common support for said toe members, the sections of said toe members being pivotally attached adjacent 20 to their larger ends to said common support, and revolvable thereon on their longitudinal axes.

5. The combination with a multiple number of longitudinally divided toe members, 25 of a common supporting means therefor,

each toe member being provided with an annular groove at its larger end in which said common support engages, said toe members being revolvable in said support on their longitudinal axes, the sections of each 30 toe member being provided with a common tapered internal screw thread, and a central screw engageable therewith for expanding the same.

6. The combination with a multiple number of longitudinally divided toe members, 35 of a common supporting means therefor, each toe member being provided with an annular groove at its larger end in which said common support engages, said toe members being revolvable in said support on 40 their longitudinal axes, the sections of each toe member being provided with a common tapered internal screw thread, and a central screw engageable therewith for expanding 45 the same, and means for adjusting the tension of said support upon said toe members.

In testimony whereof I hereunto affix my signature.

EDWARD O. YOUNG.
